UNITED STATES PATENT OFFICE.

JOHN MARRIOTT DRAPER, OF BRIDGEND, ENGLAND.

APPARATUS FOR THE SEPARATION OF SUBSTANCES OF DIFFERENT SPECIFIC GRAVITIES, SUCH AS FINE COAL OR ORES AND THE LIKE.

1,323,174.

Specification of Letters Patent. Patented Nov. 25, 1919.

Application filed November 12, 1917. Serial No. 201,518.

To all whom it may concern:

Be it known that I, JOHN MARRIOTT DRAPER, a subject of the King of Great Britain, residing at New Foundry, Bridgend, in the county of Glamorgan, England, mining engineer, have invented new and useful Improvements in Apparatus for the Separation of Substances of Different Specific Gravities, Such as Fine Coal or Ores and the like, of which the following is a specification.

The present invention relates to that class of apparatus in which the component parts of substances such as fine coal or ores and the like are separated according to their different specific gravities by the action of an ascending current of water which carries the lighter portions to an overflow situated toward the upper end and the heavier portions pass downward through such current and are discharged at the bottom, and in which a balancing column of liquid is connected to the apparatus at a point intermediate of the point of entrance of the water producing the ascending current and the point of discharge, and it consists in improvements in the construction of this form of apparatus which is described in the specification of my prior Patent No. 1210916 dated 2nd January 1917.

These improvements are illustrated in the accompanying drawing, in which

Figure 1 is a vertical section of the vertical tube shaped receptacle in which the separation is effected, and

Fig. 2 a plan view thereof.

Fig. 3 is a detached plan view of the inner chamber contained in the vertical tube.

Fig. 4 is a side elevation of a set of three vertical separating tubes combined to constitute an element having a single connection with a conveyer for carrying off the heavier portions discharged from the bottom of all three tubes, and

Fig. 5 is an end elevation of Fig. 4.

In these figures 1 is the vertical tube shaped receptacle to the upper end of which the material to be separated is supplied through the feed hopper 2, and passing through the inner chamber 15 is subjected to the action of the current of liquid entering the tube 1 at 5, and which carrying the

lighter portions of the material upward with it causes them to pass out of the apparatus by the overflow 3 toward the top. 55

Beneath the point 5 the tube 1 is provided with an opening or balancing column connection 7, below which said tube is continued to convey the heavier portions of the material which fall by gravity through the 60 ascending current to a suitable conveyer 13 by which it is carried away.

According to the present improvements the balancing column connected with the tube 1 at the point 7 is composed of an 65 elongated chamber closed at the upper end and of sufficient height above the overflow at 3 to allow a considerable body of air to remain above the normal water level as the result of running the apparatus before material is fed into it from the feed chamber 2. An air cock at 17 allows the escape of air in starting the water flow and thus a normal water level to be attained both in the tube 8 and at the overflow 3. The cock 75 17 is then closed. Immediately coal or ore is supplied from the feed chamber 2, the water level rises considerably higher in tube 8 above the level of overflow 3, owing to the added resistance to the upward current 80 offered by the body of the material in the conical inner chamber 15. When cock 17 is closed and the apparatus is in operation the volume of air confined in the tube 3 above the level of the liquid therein, will 85 constitute such an elastic cushion as will enable the column of liquid acting at the point 7 on the volume of water in the separating tube 1 below the point of entrance 5 of the ascending separating current, to respond in the most sensitive manner to every fluctuation occasioned in such tube by variations in the feed of the material entering the inner chamber 15 from hopper 2, and the pulsations produced by which might 95 otherwise lead to irregularity in the material carried off through overflow 3, and of that passing out through the bottom discharge.

The upper chamber into which the feed 100 falls from hopper 2 is composed of an inner conical portion 15 which directs such material to the center of the tube 1, and which portion is provided with perforations 16

through which the ascending current entering at 5 passes, and acts upon the material therein in the most efficient manner to insure the separation and carrying of the lighter portions upward to the overflow 3. From the bottom of the conical portion 15 a downwardly depending narrow parallel or tubular portion 18 extends and terminates a certain distance above the point of entrance of the ascending current 5, where it preferably flares or opens slightly outward, thus providing an extended zone of travel downward for the material, under conditions of equal resistance in which particles forced downward by irregular feeding or by reason of abnormal shape in reference to mass can rise or fall according to their relative specific gravities, passing either with the lighter portions upward to the overflow exit 3, or continuing their downward course for discharge with the heavies at the bottom of tube 1.

The interior of the casing of the tube 1 in the vicinity of the ascending current entrance 5 is preferably provided with an upward inwardly extending web 19, and with a similar web 20 in the vicinity of the balancing column connection 7, and which have the effect of neutralizing any tendency the flow through the tube would otherwise have of producing eddy currents which would impair the efficient ascending separating action of the current on the material, the descent of which should as far as possible be in a uniform gradual vertical direction without any gyratory motion.

As shown in Figs. 4 and 5 a plurality of separating tubes 1 (preferably three as shown) constructed as hereinbefore described are preferably combined to constitute an element with a common discharge, and any suitable number of which elements may in turn be employed in connection with a conveyer 13 common to all to constitute a battery of separators.

In order to insure the independent operation of each separator of the element the discharge from each of the tubes 1 is controlled by a separate slowly rotating star valve 25 driven by a sprocket wheel and chain 26, and which is situated above the common point of connection of the three tubes constituting such element with the tube of the conveyer 13, so that each of said tubes is effectually cut off from the others, and consequently any variations occurring in one will in no way affect the action in either of the other tubes.

Each of the tubes 1 below the separating zone and above the discharge valve 25 is preferably fitted with a suitably glazed inspection opening 22 which by observation of the descending material will allow of the ascending current of liquid or the height of the overflow at 3 being adjusted should the

operation of separation not be satisfactorily progressing.

Further, a sliding sampling valve 23 may be fitted below the inspection opening 22, and a recess 24 in which valve will retain a portion of the descending material and enable such sample to be drawn out and removed for inspection before deciding to make any adjustment, without necessitating any interruption of the operation of the apparatus.

What I claim as my invention, and desire to secure by Letters Patent, is:—

1. A separator for fine material such as fine ores, fine coal and the like comprising a separating chamber having a discharge outlet for heavy material in its lower part and an overflow outlet for light material in its upper part, a hydraulic inlet connected with said separating chamber below said overflow outlet and adapted to establish an upward current in said chamber, and a tube connected at its lower end with said separating chamber between said discharge outlet and said hydraulic inlet, extending above the plane of said overflow outlet and having a closed upper end, said tube being adapted to contain a balancing column of liquid exposed to the action of an air cushion and directly connected with said separating chamber and sensitively responsive to fluctuations caused therein by irregularities of the feed of material thereto.

2. The combination of a series of separators for fine material such as fine ores, fine coal and the like each comprising a separating chamber having a discharge outlet for heavy material in its lower part and an overflow outlet for light material in its upper part, a hydraulic inlet below said overflow outlet and adapted to establish an upward current, means directly connected with each separating chamber between its outlet and inlet for maintaining a balancing column, a common conveyer tube connected with the several discharge outlets of said separating chambers and slowly rotating discharge valves severally controlling the discharge through said outlets and rendering the action of each independent of that of the others.

3. A separator for fine material such as fine ores, fine coal and the like comprising a separating chamber having a discharge outlet for heavy material in its lower part and an overflow outlet for light material in its upper part, a hydraulic inlet connected with said separating chamber below said overflow outlet and adapted to establish an upward current in said chamber, and a tube connected at its lower end with said separating chambers between said discharge outlet and said hydraulic inlet, extending above the plane of said overflow outlet and having a closed upper end provided with an air cock,

said tube being adapted to contain a balancing column of liquid exposed to the action of an air cushion and directly connected with said separating chamber and sensitively responsive to fluctuations caused by irregularities of the feed of material thereto.

In testimony whereof I have signed my

name to this specification in the presence of two subscribing witnesses.

JOHN MARRIOTT DRAPER.
